US0D1077061S

(12) **United States Design Patent** (10) **Patent No.:** **US D1,077,061 S**
(45) **Date of Patent:** **** May 27, 2025**

(54) **WIGGLE CAR**

(71) Applicant: **Shenzhen Fanttik Technology Innovation Co., Ltd.**, Guangdong (CN)

(72) Inventor: **Xiang Zhou**, Guangdong (CN)

(73) Assignee: **Shenzhen Fanttik Technology Innovation Co., Ltd.**, Guangdong (CN)

(**) Term: **15 Years**

(21) Appl. No.: **29/981,115**

(22) Filed: **Dec. 29, 2024**

(30) **Foreign Application Priority Data**

Dec. 16, 2024 (EM) 015085343-0001

(51) **LOC (15) Cl.** **21-01**

(52) **U.S. Cl.**

USPC **D21/424**; D21/426

(58) **Field of Classification Search**

USPC D21/423, 424, 425, 426, 427, 432, 433, D21/435, 533, 538, 548, 581; D12/112

(57) **CLAIM**

The ornamental design for a wiggle car as shown and described.

DESCRIPTION

FIG. 1 is a front, right and top perspective view of a wiggle car, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the wiggle car that form no part of the claimed design.

1 Claim, 8 Drawing Sheets
